CLAIM

The ornamental design for a mirror light, as shown and described.

DESCRIPTION

FIG. 1 is a front, right and top perspective view of a mirror light, showing my new design;

FIG. 2 is a front view thereof;

FIG. 3 is a rear view thereof;

FIG. 4 is a right side view thereof;

FIG. 5 is a left side view thereof;

FIG. 6 is a top plan view thereof; and,

FIG. 7 is a bottom plan view thereof.

The broken lines in the drawings indicate a boundary between claimed and unclaimed portions, and form no part of the claim. The deemphasized, grayscale portions shown inside the broken line boundaries form no part of the claimed design.
